FOOD BEATER

William Marcus, Cleveland, Ohio, assignor to Merrymaid Plastics Corporation, Cleveland, Ohio

Filed Mar. 31, 1964, Ser. No. 79,276

Term of patent 14 years

(Cl. D44—1)

FIGURE 3 is an end elevational view thereof as viewed from the handle end and on a scale enlarged with respect to FIGURE 2; and

I claim:

The ornamental design for a food beater, as shown.
